UNITED STATES PATENT OFFICE.

FRANCIS H. RICHARDS, OF SPRINGFIELD, MASS., ASSIGNOR OF ONE-HALF
TO THE PRATT & WHITNEY COMPANY, OF HARTFORD, CONN.

BLANK-FEEDING MECHANISM.

SPECIFICATION forming part of Letters Patent No. 331,443, dated December 1, 1885.

Application filed October 16, 1884. Serial No. 145,663. (No model.)

To all whom it may concern:

Be it known that I, FRANCIS H. RICHARDS, a citizen of the United States, residing at Springfield, in the county of Hampden, State 5 of Massachusetts, have invented certain new and useful Improvements in Blank-Feeding Mechanisms, of which the following is a specification, reference being had to the accompanying drawings, forming a part thereof, in 10 which—

Figure 1 is a plan view of a mechanism embodying my improvement, the front side of the mechanism being at the bottom of the figure. Fig. 2 is a similar view of the same, 15 partially in section. Fig. 3 is a front elevation of the same, except the rear columns, together with certain parts of an envelope-machine shown above it. Figs. 4 and 5 show some of the said parts in different positions. 20 Fig. 6 is an enlarged front elevation, partially in section. Fig. 7 is a plan view of a part of Fig. 6.

Similar reference-characters refer to similar parts throughout all the views.

This invention relates to that class of blank-feeding mechanisms which are used for feeding blanks of paper previously cut to the required shape to machines for making said blanks into envelopes, boxes, or other articles, as the case 30 may be.

The object of my invention is to furnish an improved mechanism whereby the feeding of the blanks may be carried on continuously without being interrupted by the operation 35 of replenishing the pile of blanks. This object I have heretofore attained by means of certain improvements described and claimed by me in United States Patent No. 284,483; but I now attain the same object in a more 40 convenient way by means of the improvements which I will herein first describe in connection with the drawings, and afterward specifically point out in the claims.

In the drawings, C is a part of a machine-frame, and A is the base of the feeding mechanism supported thereon. This base has four columns, A', rising therefrom, arranged as shown in Figs. 1 and 2, those on the front side being farthest apart. Each of these columns 45 has on its inner side two channels, J, and each

channel has a pair of racks having a series of ratchet-teeth on them, as shown best in Fig. 6. At their upper ends these racks are adapted to have a lateral movement in the direction of their width, which movement is produced by a spring, as D, and limited by a downward projection on the caps A⁶ of columns A'. (See Fig. 6.) The screws D' are for the purpose of holding those springs in place vertically and for adjusting their tension. One rack of each pair of them extends from the upper surface of frame C, or from some other fixed point, up to the under surface of cap A⁶, so that it cannot have any vertical movement. This rack is shown at 55 A³ and A⁵, being the front one of each pair. The other racks, A² and A⁴, being the back one of each pair, are made somewhat shorter, so they may have a vertically-reciprocating motion slightly in excess of the length of one 60 rack-tooth. This vertical motion is imparted to these racks A² and A⁴ by means of arms T, fixed on rock-shafts T', which shafts are oscillated by means of rod R, acting through lever R⁴, lever R², rod R', and lever R³. The 65 ends of arms T fit closely into notches in racks A² and A⁴, (see A⁴, Fig. 6;) but in the racks A³ and A⁵ these notches are so long vertically that these racks do not restrict the movement 70 of said arms. (See A⁵, Fig. 6.)

The construction of the above mechanism is such that all of the vertically-movable racks are moved in the same time and direction through equal distances. The racks at their upper ends are movable laterally independently of each other.

It is the function of the front racks to hold up and of the back racks to lift step by step the blank-supporting plates P' and P², which plates are of similar construction, but vary 85 somewhat in size, (see Fig. 1,) so that the forward pair of racks in each column operate to feed up one plate, P', and the back pair to feed up plate P². These plates are beveled where they rest on the racks, as at P' in Fig. 90 6, and the rack-teeth are inclined, (see at M, Fig. 6,) so their weight will tend to hold the plates rearward against the front column at A', Figs. 1 and 2.

When the form of the blank requires it, 95

arms, as V, may extend from the plates outside of the front columns, and rearward under the projecting ends of the blanks, as in Figs. 1 and 2. This form of plate is best for supporting envelope-blanks, (the kind shown in the drawings,) because it permits the use of the fixed guides B', Figs. 1 and 2, usually employed for holding the pile of blanks B from lateral movement. The front pair of these guides are secured to the caps A⁶, and extend downward but little farther than the rack-teeth. The back pair extend preferably down to the base A. A vertical lifter-slide, L, having a top plate, P, is located between columns A' and furnished with some device (not shown) whereby it may be slid up and down by the operator, as hereinafter described. The mode of using this lifter and the blank-supporting plates is as follows:

25 When a pile of blanks is to be placed in the machine, slide L is dropped until P is in its lowest position. (Indicated by dotted lines in Fig. 6.) One of the blank-supporting plates is then properly placed on that top plate 25 and the blanks placed on their plate and pushed back against the back guides. Slide L is now raised until the plate thereon is caught between and held up by the teeth of the racks, as at P', Fig. 6. The slide L is 30 now lowered to its former position, the other blank-supporting plate placed thereon, and another pile fed up, as before. During this time, if the machine has been running, the first pile will have been fed up to the position 35 W, Fig. 3, making room below it between the rack-teeth for pile Y to be fed up against it. When this has been done, the plate under the first pile is withdrawn and used as before for feeding a third pile up to the second one, 40 and thus the feeding of the piles of blanks is made continuous without interrupting the operation of the machine.

The operation of the racks and their rock-shaft or other equivalent driving mechanism 45 to lift the plates P' and P² will be readily understood from the drawings and preceding description. The object of this mechanism being to transmit a reciprocating motion from rod R to the rack, it is obvious that any other 50 mechanism which will do the same thing will be an equivalent for it in this place.

Referring now to Figs. 3, 4, and 5, H is a slide carrying an ordinary blank-picker, which is shown in its middle position at P', in its lower position on the blank-pile at P³, and in its upper gum-receiving position at P⁵. This slide H, with its picker P⁴, corresponds with "picker a" in the aforesaid patent. The line B represents a single blank as it is 60 when lifted up by the picker. Parts 16, 9, 10, 11, 12, 7, and 8, constituting a latch-and-lever mechanism, correspond substantially, both in their construction and operation to the same parts in said patent, to which reference may be had for a particular description of the same. By referring thereto it will be seen that the object of this mechanism is

for controlling the action of said mechanism for elevating the pile of blanks by the varying movements of said gummers (pickers) as 70 they pick up the blanks and reduce the height of the blank-pile. These controlling devices, as shown in that patent, act to elevate the blank-supporting plate by turning a set of vertical-elevating screws, while in my present 75 invention they operate the vertically-elevating rack-rods R and the rock-shaft mechanism for the same purpose. When slide H, passing downward, carries arm 16 by latch 9 (see Fig. 4) so far as to allow the ends of 80 said latch to snap past it, as at Z, Fig. 3, said slide will, on its return upward, when the position in Fig. 3 is reached, cause an oscillating movement of lever 7 in the direction of arrow J in Fig. 4. This upward motion continuing brings the said arm 16 to position X, Fig. 3, allowing lever 7 to return to its normal position, (shown in Figs. 4 and 5,) when said latch slips by arm 16 and falls against stop 12, ready for the next operation. 85 If the pile of blanks is so high as to stop the descending slide H before arm 16 reaches said position Z, it is obvious no motion will then be imparted thereby to lever 7, and consequently the said pile will not be fed up. 90 The picker will then continue to take up blanks one at a time from the pile until it can descend sufficiently low to bring said arm to said position, when it will again feed up the pile as before. The frequency with which 100 this feeding will occur depends, obviously, upon the speed of the machine and the relation existing between the height of a rack-tooth and the thickness of one blank.

Having thus described my invention, I 105 claim—

1. A frame-work and a series of columns supported thereon, of which each one is adapted to receive and hold in place a pair of racks, a pair of racks to each column held in place 110 thereby, a blank-supporting plate fed up by said racks, and a reciprocating mechanism, substantially as described, for operating said racks to feed up said plate, all combined and operating substantially as set forth. 115

2. A frame-work and a series of columns supported thereon, of which columns each one receives and holds in place two pairs of racks, two pairs of racks to each column, of which 120 two pairs one pair in each column acts upon one blank-supporting plate and the other pair upon another plate, the two blank-supporting plates, and a reciprocating mechanism, substantially as described, for operating said racks up to said plates, all combined and operating substantially as set forth. 125

3. In combination, a suitable column, as A', rack A⁴, rack A⁵, spring D, cap A⁶, arm T, and shaft T', substantially as described.

4. In combination, a series of racks, as A², having teeth inclined, as at M, Fig. 6, and a blank-supporting plate, as P', fitted thereto, substantially as and for the purpose described. 130

5. A series of racks supported and oper-

ating substantially as described, a blank-supporting plate, as P', and plate-lifter L, all combined substantially as and for the purpose set forth.

5 6. A series of columns having a series of racks, substantially as described, the rock-shaft mechanism for operating said racks, slide H, having picker P' and arm 16, a latch-and-lever mechanism, substantially as de-

scribed, and a connecting rod or part between 10 said latch-and-lever and said rock-shaft mechanisms, all combined and operating substantially as set forth.

FRANCIS H. RICHARDS.
